UNITED STATES PATENT OFFICE.

ROBERT SANFORD RILEY, OF WORCESTER, MASSACHUSETTS, ASSIGNOR TO S. RILEY STOKER CORPORATION, OF WORCESTER, MASSACHUSETTS, A CORPORATION OF MASSACHUSETTS.

SIDE-WALL CONSTRUCTION FOR FURNACES.

Application filed August 22, 1923. Serial No. 658,799.

This invention relates to furnaces of the type in which an automatic underfeed of fuel is provided by a suitable stoker mechanism. The fuel is fed into the stoker retorts at the front ends thereof and is forced rearward and upward therefrom to replenish the burning fuel bed. In the operation of such furnaces, clinkers and slag frequently adhere to the furnace side walls in such quantities as to interfere with the efficient operation of the furnace. Certain kinds and grades of fuel are particularly troublesome in this respect.

It is the object of my invention to provide an improved construction of furnace side wall which will effectually prevent the adhesion of clinker or slag thereto and which will thus permit the furnace to operate with increased efficiency and which will also avoid the expenditure of time and labor heretofore required for periodically cleaning and repairing the side walls.

To the attainment of these objects, I provide sectional air admitting side wall structures adjacent the outer edges of the fuel bed and I also provide means for regularly reciprocating or otherwise moving these side wall structures. The combination of air cooling of the sectional side wall structure, air admission to the fuel adjacent thereto, and relative movement between the sectional wall structure and the fuel bed effectually prevents the adherence of slag and clinker to the furnace side wall.

Further features of my invention relate to certain arrangements and combinations of parts which will be hereinafter described and more particularly pointed out in the appended claims.

A preferred form of the invention is shown in the drawings, in which—

Fig. 1 is a partial plan view of a stoker embodying my improvements;

Fig. 2 is a sectional elevation taken along the line 2—2 in Fig. 1;

Fig. 3 is an enlarged side elevation partly in section, showing a portion of the movable side wall structure;

Fig. 4 is a transverse sectional elevation taken along the line 4—4 in Fig. 3;

Fig. 5 is a perspective view of the component parts of the side wall structure, spaced apart but otherwise substantially in their normal relation;

Fig. 6 is a side view of a detail part, and 55
Fig. 7 is a transverse sectional view through a side wall and adjacent retorts.

Referring to the drawings, I have shown my improved side wall structure embodied in an underfeed furnace or stoker which is otherwise of a usual commercial type and comprises a plurality of retorts 10 (Figs. 1 and 2) separated by retort side walls 11, each supporting a series of tuyère blocks 12. A plunger or ram 13 for each retort operates to feed fuel from a hopper 14 to the front end of its respective retort. The rams or plungers 13 are driven through connecting rods 15 by a crank shaft 16 which may be actuated from a motor 17 through a worm gear 18, worm 19 and worm wheel 20 or in any other convenient manner.

A plate 21 forms the bottom of the retort and overfeed grates 22 extend across the rear ends of the retorts, over which grates the ash and fuel are moved to the dumping or discharge plates 22^a. At the outer side of the retort, adjacent the furnace side wall W, I provide a side wall plate 23 which is connected for reciprocation with the adjacent plunger 13.

For this purpose the side wall plate 23 is provided at its front end with eye-bolts 24 secured in slots in the end of the plate and forming a pivotal bearing for a side plate rod 25 having a bolt 26 threaded into the front end thereof. The bolt 26 extends through a transverse opening in a stud 27 projecting inward through a slot in the plunger cylinder and movable with the plunger 13. As the plunger is reciprocated by rotation of the crank shaft 16, the stud 27 is also reciprocated, engaging the head of the bolt 26 on its forward stroke and engaging the end of the side plate rod 25 on its rearward stroke. The side wall plate 23 thus has a lost motion connection with the plunger 13 and is movable therewith for a portion of each stroke of the plunger. The motion of the side wall plate 23 may be increased by placing one or more U-shaped collars 28 (Fig. 6) on the bolt 26 to reduce the lost motion.

My improved air admitting side wall structure is mounted upon the upper edge of the side wall plate 23 and preferably comprises the series of parts shown in detail in Fig. 5. These parts comprise a

upper block 30, intermediate blocks 31, a bottom block 32, and front and rear ribbed bars 33 and 34. The intermediate blocks 31 and the bottom blocks 32 are of hollow section and the parts when assembled have the relation indicated in Figs. 3 and 4. The parts when thus assembled are secured in position by bolts 35 extending obliquely upward through the blocks from a flange 36 10 at the lower edge of the side wall plate 23.

The ribbed bars 33 and 34 are mounted in recesses or openings between adjacent blocks and thus provide air admitting openings in the wall structure. It will be understood that a single bottom block 32 and a single top block 30 are used for each side wall structure but that the number of intermediate blocks and bars will depend upon the size of the furnace and particularly 20 upon the length of the retort. Air under pressure is supplied to the recess or passage 37 behind the side wall plate 23 and passes upward through the blocks as indicated by the arrows *a* in Fig. 4 until it passes out 25 through the openings around the different ribbed bars 33 and 34 to the fuel bed adjacent thereto.

The side wall structure is thus cooled by the passage of air therethrough and also 30 provides an air supply for the fuel bed, while at the same time its continued reciprocation assists in preventing the adherence of slag or clinker thereto. The relative elevations of the retort walls 11 and tuyère 35 blocks 12 in comparison with the side wall structure is clearly shown in Fig. 7.

It will be seen that the movable side wall structure extends substantially above the line of the usual tuyère blocks between the 40 retorts and that it protects the furnace side wall substantially to the upper limit of clinker formation. Should any of the blocks or other parts become burned or broken in operation, the whole structure is 45 easily separated by removing the bolts 35, thus permitting easy replacement of damaged parts.

Having thus described my invention and the advantages thereof, I do not wish to be limited to the details herein disclosed otherwise than as set forth in the claims but what I claim is:

1. In an underfeed furnace, a furnace side wall, a plurality of rearwardly and downwardly inclined retorts inside the furnace, 50 means to feed fuel to said retorts, and a sectional wall structure arranged to reciprocate adjacent said furnace side wall, said wall structure extending above the plane of the tops of the retort walls and comprising 55 sections vertically spaced to admit air therebetween to the fuel substantially above said plane.

2. In an underfeed furnace, an air admitting side wall structure comprising a top 60 block, a bottom block, a plurality of intermediate blocks, said blocks having portions spaced apart to provide air openings, and ribbed bars mounted in said openings.

3. In an underfeed furnace, an air admitting side wall structure comprising a top 70 block, a bottom block, a plurality of intermediate blocks, said bottom and intermediate blocks being hollow and being formed to provide air openings when placed together, and ribbed bars mounted in said 75 openings.

4. In an underfeed furnace, a furnace side wall, a plurality of rearwardly and downwardly inclined retorts in said furnace, an 80 air admitting wall structure adjacent said furnace side wall and extending rearwardly and downwardly at substantially the angle of the tops of the retort walls with its upper edge substantially above the plane of the 85 tops of said retort walls, said wall structure comprising sections vertically spaced to admit air therebetween to the fuel substantially above said plane, and means to reciprocate said wall structure longitudinally of said furnace and retorts.

In testimony whereof I have hereunto affixed my signature.

ROBERT SANFORD RILEY,
